UNITED STATES PATENT OFFICE.

VICTOR YBURETA, OF BUENOS AIRES, ARGENTINA.

APPARATUS FOR ADMITTING ADDITIONAL HEATED AIR INTO INTERNAL-COMBUSTION ENGINES.

1,417,127.

Specification of Letters Patent. Patented May 23, 1922.

Application filed April 18, 1919. Serial No. 291,039.

To all whom it may concern:

Be it known that I, VICTOR YBURETA, citizen of the Argentine Republic, residing at No. 332 Chacabuco Street, Buenos Aires, Argentina, have invented certain new and useful Improvements in Apparatus for Admitting Additional Heated Air into Internal-Combustion Engines, of which the following is a specification.

10 My invention relates to a novel apparatus for heating and admitting air, and has for its object to provide for a very simple apparatus which may be applied to the air and gas inlet pipes of carburetors of internal combustion engines, particularly to those of the so-called Ford type.

Said apparatus, when connected to the inlet pipe of such motors, admits a flow of hot air which fosters the combustion of the gases, 20 thereby regulating the working of the engine and allowing a considerable economy in the fuel.

In order that my present invention may be clearly understood and easily carried into practice I have illustrated it in the accompanying sheets of drawings, which show a preferred embodiment of the said invention, such as may be applied to a Ford type of engine.

30 In the said drawings,

Figure 1 is a perspective view showing the apparatus full size.

Figure 2 is a front view of the air and gas inlet pipe connected with the carburetor 35 in the Ford engine.

Figure 3 shows the rear side of the said inlet tube.

Figure 4 is a transverse section of the apparatus.

40 Figure 5 is a vertical section on line 5—5 of Figure 4.

Figure 6 is a longitudinal sectional view of the tube by means of which the apparatus is connected to the inlet tube.

45 Figure 7 shows the intermediate plate.

Similar characters of reference denote like parts throughout the said drawings.

The apparatus consists of a cylindrical iron or like receptacle having at the upper 50 end a flange on which the cover may be seated. Said cover is firmly held in position by means of a screw I, a nut J and a cross-pin K, whereby an air-tight joint is formed. To this end it has been found ad-

visable to surround the said upper flange 55 with asbestos fibre or the like.

Within the receptacle and resting on its bottom there is a quantity of the finest copper wire, its object being to take up heat and to provide for an extensive heat-radiating surface when the atmospheric air enters the apparatus.

On the said cover there is a cylindrical hollow extension A provided with a valve member H which controls the entrance of atmospheric air into the said receptacle. Said extension and valve member are clearly shown in Figures 4 and 5. The stem of valve H is surrounded by a spiral steel spring R which bears at its upper end 65 against a head L mounted on the stem end, the latter having a reduced and threaded terminal which is fitted with a nut M, said nut engaging the upper face of head L and being locked in position by a cross-pin n. 70 The lower end of spring R bears upon the adjacent end of the part A, which is reduced, as shown at G to provide a seating for the valve.

As may be seen from Figure 5 the two 80 openings O and O' in the said reduced end G allow the entrance of atmospheric air.

As the suction of the air is produced by the working of the engine, the said valve H seats and unseats rapidly, thereby regulating the admission of atmospheric air within the apparatus.

The air, on entering the receptacle through the openings O, O' and the extension A, is forced to make a long course in close contact with the copper wire, to which end a downwardly-convexed baffle or deflecting plate N—N (Fig. 4) is provided. The said wire is rapidly heated by the working of the engine and maintains a uniform temperature.

The heated air is withdrawn from the receptacle by the suction of the engine through the outlet E' and the intermediate connecting tube E—F, the end E of the latter being threaded in the said outlet E', and enters the inlet pipe at F', at which point the end F of the tube is attached to the inlet pipe. The hot air thus supplied to the inlet pipe is added to the explosive mixture which enters the end C of the pipe from the carburetor, the result being an appreciable saving of naphtha.

The apparatus is held in position by means of a steel plate P.

It is obvious that many constructive and other changes may be introduced without departing from the present invention the scope of which is clearly set forth in the appended claiming clauses.

Having now fully described and ascertained the nature of my present invention 10 and in what manner the same is to be carried into practice I declare that what I claim is:

An apparatus for supplying auxiliary heated air to internal combustion engines, 15 comprising a metal receptacle adapted to be secured sufficiently close to the engine to be heated thereby; an upstanding valve casing on the top wall of the receptacle opening thereinto at its lower end and provided adjacent its upper end with an air inlet; a spring-controlled valve in said casing normally closing said inlet to prevent admis-

sion of air into the receptacle; an upstanding outlet member also on the top wall of the receptacle and opening therethrough; a 25 connecting tube having one end engaged in said outlet member and the other end opening into the inlet pipe of the engine, whereby the engine suction exerted through said inlet pipe will open said valve and cause 30 a current of atmospheric air to be drawn through said inlet successively into and through the valve casing, the receptacle and outlet member, the connecting tube and the inlet pipe and into the engine; and a mass 35 of fine heat-conducting material disposed within the receptacle in the path of the air current and adapted to be heated by its contact with the walls of the receptacle and to heat said air current during the passage 40 of the latter through the receptacle.

In testimony whereof I affix my signature.

VICTOR YRURETA.
